UNITED STATES PATENT OFFICE.

ABNER S. COOK, OF BURLINGTON, IOWA.

LETTER-BOX.

SPECIFICATION forming part of Letters Patent No. 350,041, dated September 28, 1886.

Application filed February 4, 1886. Serial No. 190,844. (No model.)

To all whom it may concern:

Be it known that I, ABNER S. COOK, a citizen of the United States, residing at Burlington, in the county of Des Moines and State of Iowa, have invented a new and useful Improvement in Letter-Boxes, of which the following is a specification.

My invention relates to improvements in letter-boxes in which the bottom and a front flap are joined at right angles in one piece and hinged to the box, and the object of my invention is to provide a letter-box for private use, simple in construction and easily examined and emptied. I accomplish this by the device hereinafter described, and illustrated in the accompanying drawing, in which similar letters refer to similar parts.

In the drawing, A is the box of any suitable material, preferably of iron, furnished with a perforated top, T, to admit letters, papers, and other mail-matter.

L is a lid attached by any suitable hinge or similar device to the top or back of the box, so as to fit close over the top T.

B is a combined bottom and front flap solidly fastened together at right angles, and provided with lugs b b, which lugs freely move in perforations c c in the box A, so as to form a hinge. B also is provided with a hasp, d, or any other suitable fastening device, which fits over a staple, d', in box A, and thus admits of being fastened and locked. The combined bot-

tom and front flap, B, is provided with window W.

X is a ridge below B upon the back of box A. 35

The operation of my invention is as follows: The mail-matter is put into the box A through the perforated top T by lifting lid L. If now, the box is to be emptied of its contents, the front flap of B is opened and pressed down, 40 whereby the bottom will be lifted upward and forward, thus bringing any mail-matter contained in the box toward the front opening, where it can easily be taken out.

The object of having ridge X is to prevent 45 the sliding of the mail-matter out of the box back of the movable bottom.

By means of window W it can be easily seen whether mail-matter is contained in the box or not. 50

What I claim as my invention, and desire to secure by Letters Patent, is—

The combination, with a letter-box provided with a perforated top and a lid, of a combined bottom and front flap, B, arranged at right angles, said flap being provided at its angle with lugs b, which bear in the perforations c to form hinges, and a ridge or stop, X, substantially as described. 55

ABNER S. COOK.
